LEWIS M. ELLISON, OF EVANSTON, ILLINOIS

DRAFT GAUGE

Application filed September 21, 1932. Serial No. 634,125.

This invention relates to furnace draft gauges of the sealed gasometer bell type.

The main object of the invention is to provide valve means in association with the bell and the draft tube extending into the same for automatically venting the bell to the atmosphere and closing the tube to shut off the draft to the bell under periods of excess minus pressures or drafts produced in the bell 10 during the operation of the gauge so as to relieve such pressure and prevent the sealing liquid at the lower end of the bell being drawn out of the same through the tube.

A further object of the invention is to have 15 the valve means carried by the bell above the tube so that the valve will act to open the bell and close the tube on the lowering of the bell sufficiently to seat the valve on the tube.

Another object of the invention is to provide 20 the valve means with valve members in the form of discs on opposite sides of the head of the bell and respectively controlling the vent opening in the bell head and the opening at the upper end of the draft tube within the bell.

A further object of the invention is to connect 25 the valve members by a stem extending through the opening in the bell head, whereby the valve means is in the form of a single fixture capable of a double action in sealing the bell under normal minus pressures and 30 venting the bell and closing the tube under periods of excess minus pressures.

The invention consists further in the features hereinafter described and claimed.

In the accompanying drawings:

Fig. 1 is a front view of a draft gauge embodying the double acting valve of my invention;

Fig. 2 is a view looking into the gauge with the cover section removed, parts of the gauge structure being broken away and in section respectively for the purpose of illustration;

Fig. 3 is a vertical sectional view taken on line 3—3 of Fig. 2;

Fig. 4 is a view showing the valve in draft tube closing and bell venting position;

Fig. 5 is a vertical sectional view taken on line 5—5 of Fig. 4; and

Fig. 6 is a horizontal sectional view

through the stem of the valve to show the longitudinal vent passages therein.

As shown in the drawings, the gauge comprises a box-like outer casing having a body section 1 and a removable cover section 2. 55 The latter constitutes the front wall of the casing and is detachably secured thereto by marginally disposed screws 3 as shown. The cover section is provided with a pair of sight openings 4, 5 arranged one above the other, 60 the opening 4 permitting a view to be had into the casing to ascertain the level of the oil in the pan or reservoir 6 located within the casing for the inverted gasometer bell 7 with which the valve means of my invention 65 is employed.

The opening 5 permits a view to be had of the scale 8 over which moves a pointer 9 at the outer or free end of an arm 10 connected to and movable by a lever 11 fulcrumed between its ends within the casing above the bell 7 as shown in Figs. 2 and 3. The scale 8 is preferably marked on a strip of cardboard or other suitable sheet material which is mounted in a holder 12 secured in the casing to the rear of the cover by screws 13 as shown. A transparent plate 14 of glass or other suitable material covers the outer end of the body section 1 and is held in place by the cover as shown in Fig. 3. 75

The bell 7 is suspended from one end of the lever 11 by a yoke 15, which as shown in Figs. 4 and 5, is hung on a stud 16 fixed to and projecting laterally from one side of the lever. The yoke has an opening to receive the stud and the latter is provided between its ends with a reduced portion providing a knife-edge bearing for the yoke. The arms 17, 17 of the yoke are secured at their lower ends, as by screws 18, to the top wall or head 19 of the bell. Said head, as shown, is in the form of a flanged cap fitted over the upper end of the bell and is hermetically sealed thereto. 85

The lower end of the bell, which is open, extends into the reservoir 6 and is sealed by a body of oil or other sealing liquid contained therein. A draft tube 20 extends upwardly into the bell from the reservoir through the liquid seal and terminates short of the bell head. Said tube extends to the 90 100

exterior of the casing through its bottom wall and is there provided with a threaded nipple whereby the tube may be connected to the source of pressure to be indicated by the gauge.

5 The bell head 19 is provided between the legs of the yoke with an opening 21 through which extends the stem 22 of the double acting check valve of my invention. This stem 10 fits the opening to hold the valve central with respect to the bell and is provided with longitudinal grooves 23 to vent the bell to the atmosphere when the valve member 24 at the upper end of the stem and exterior of the bell uncovers the opening in the bell head as shown in Figs. 4 and 5. At this time the valve member 25 at the lower end of the stem and within the bell is seated on the upper end of the draft tube, 15 The valve members 24, 25 are at the opposite ends of the stem 22 and are in the form of discs to seat on the edges of the openings which they respectively control. The bell head 19 is pressed upward into tubular form 25 about the opening 21 to provide a more effective seating surface for the valve member for such opening. The upper end of the draft tube may be made adjustable by providing it in the form of a sleeve 20 having threaded 30 connection with the tube.

The gauge of the drawings is designed for minus pressures. In the normal operation of the gauge, the valve is carried by the bell above and out of contact with the draft tube 20. The opening 21 in the bell head is closed at this time by the upper member 24 seating on the bell head about the opening, as shown in Fig. 2. Thus the interior of the bell is closed to the atmosphere and it may rise 40 and lower in response to the changes of minus pressure produced within the bell through the tube 20. The bell may move within the scale range of the gauge without disturbing the position of the valve closing the opening 45 in the top of the bell. When the interior of the bell is subjected to an excessive minus pressure, the bell lowers below the range of its normal movement and carries the valve into contact with the upper end of draft tube 50 20, closing the same and shutting off the pressure to the bell. This transfers the support of the valve from the bell to the tube, and permits the bell to lower with respect to the valve. As the bell lowers, it moves away from the valve member 24 uncovering opening 21 and venting the interior of the bell to the atmosphere. This relieves the pressure within the bell, and the liquid which has been unduly raised above the seal is prevented 60 from rising far enough to reach the upper end of the draft tube. Thus no opportunity is afforded for drawing the oil out of the seal through the draft tube under these periods of excess minus drafts. When the pressure 65 within the bell is relieved the bell rises and

lifts the valve from the tube. This closes the interior of the bell to the atmosphere, and the bell is conditioned for normal operation, if the excess pressure has subsided. The advantages of the double check valve are that 70 the bell is relieved of excess minus drafts or pressures whenever they occur, and drawing of the sealing liquid out of the bell through the draft tube is prevented. Thus the gauge may be built within practical limits, as the bell and draft tube need not be made unduly long to compensate for what would be the maximum rise of liquid in the bell under a maximum excess minus draft.

The fulcrum 26 for the lever 11 is supported by a bracket 27 secured to and depending from the top wall of the casing section 1. The lever is provided with a counter-weight 28 at its end opposite the bell, and the pointer arm has a gravity load 29 as in gauge devices of this general character. The reservoir is filled through a filling tube 30 which extends through the top valve of the casing, said tube having a closing cap at its outer end as shown. The reservoir has a drain fitting 31 at its bottom wall, said fitting being normally closed by a cap as shown.

The details of construction and arrangement of parts shown and described may be variously changed and modified without departing from the spirit and scope of my invention except as pointed out in the appended claims.

I claim as my invention:

1. In a draft gauge of the character described having an indicating mechanism, an inverted gasometer bell for actuating the same, a liquid seal for the lower end of the bell, a draft tube opening into the bell above the seal, a vent opening in the bell above the tube, and valve means carried by the bell and normally closing the vent opening therein when supported by the bell out of contact with the tube, said valve means acting to close the tube when brought into contact therewith in the depression of the bell by an excess minus pressure therein and opening the vent in the bell to relieve said pressure to prevent drawing of the sealing liquid out of the bell through the tube.

2. In a draft gauge of the character described having an indicating mechanism, an inverted gasometer bell for actuating the same, a liquid seal for the lower end of the bell, a draft tube opening into the bell above the seal, a vent opening in the head of the bell above the tube, and valve means carried by the bell and normally closing the vent opening therein when supported by the bell out of contact with the tube, said valve means acting to close the tube when seated thereon in the depression of the bell by an excess minus pressure therein and opening the vent in the bell to relieve said pressure to prevent drawing of the sealing liquid out of the bell.

through the tube, the head of the bell about the vent opening being projected into tubular form above the bell to provide a seat for the valve.

5 3. In a draft gauge of the character described having an indicating mechanism, an inverted gasometer bell for actuating the same, a liquid seal for the lower end of the bell, a draft tube opening into the bell above

the seal, and valve means carried by the bell above the tube, said valve means having a stem extending through a vent opening in the head of the bell and disc-like members at the opposite ends of said stem for opening and closing the upper end of the tube and the vent opening, respectively.

LEWIS M. ELLISON.
